UNITED STATES PATENT OFFICE.

THOMAS ELCANAH MILLER, OF TACOMA, WASHINGTON.

WRENCH.

1,298,997.

Specification of Letters Patent.

Patented Apr. 1, 1919.

Application filed July 31, 1918. Serial No. 247,665.

To all whom it may concern:

Be it known that I, THOMAS ELCANAH MILLER, a citizen of the United States, and a resident of Tacoma, in the county of 5 Pierce and State of Washington, have made certain new and useful Improvements in Wrenches, of which the following is a specification.

My present invention relates generally to 10 wrenches, and more particularly to a quick adjustable wrench, which will fit various types and sizes of nuts, and which may be readily adjusted from the handle in order to bring about proper engagement of such 15 nuts.

In its more specific aspect, my invention resides in the features of construction, arrangement and operation to be now described with respect to the accompanying drawings 20 forming a part of this specification, and in which:—

Figure 1 is a perspective view illustrating my complete wrench;

Fig. 2 is a vertical longitudinal section 25 taken therethrough;

Fig. 3 is a vertical transverse section taken substantially on line 3—3 of Fig. 2; and,

Fig. 4 is a detached perspective view of 30 the thumb piece and its ratchet engaging parts.

Referring now to these figures, the elongated handle 10 of my improved wrench has a lengthwise slot 11, which results in the U- 35 shape of its walls, as seen in the cross section Fig. 3, this handle being provided at one end with an angular integral jaw 12, and with a slotted angular extension 13 at right angles to the jaw 10, the slot of which 40 appears at 14 and slidably receives the inner toothed extension 15 of a movable jaw 16, whose range is limited to the length of the extension 13, and by certain other parts, as presently described.

45 In the angle between the handle 10 and its extension 13, is journaled a toothed wheel 17, the inner portion of the extension 15 of the movable jaw 16 being toothed at 18 and engaged by the said toothed wheel, the latter in turn engaged by the toothed forward portion 19 of an adjusting slide 20, movable in the slot 11 of the handle and controlled in such movement through the coöperation

of movable ratchet pieces 21 and 22, with a stationary ratchet piece 23, the latter of 55 which is set into and is rigid with the handle 10 at a point intermediate its ends.

The slide 20 is slotted intermediate its ends to receive the reduced inner portion 24 of a thumb piece 25, which latter projects 60 beyond the side walls of the handle so as to be readily engaged by the thumb of the user while the handle 10 is grasped. This thumb piece 25 is movable on a pivot 26 carried by the slide 20, and has at its forward end an 65 extension which forms the ratchet member 22, as most plainly seen in Fig. 4. This ratchet member is thus movable vertically into and out of engagement with the ratchet piece 23, by virtue of the tilting of the 70 thumb piece 25 upon its pivot 26.

The thumb piece 25 is also provided with a forward cut away portion above the toothed extension 22, and the said cut away portion has a rounded inner end 27 so as to 75 receive the ratchet member 21, the rounded end 28 of which movably interfits the inner end 27 of the cut away portion just previously described, to permit the ratchet member 21 to yield vertically with respect to the 80 thumb piece, and to a limited extent beyond which it is movable with the thumb piece when the latter is tilted on pivot 26.

The slide 20 has a spring 29 secured thereto which bears upon the ratchet member 21, 85 and thus through the latter normally holds the forward end of the thumb piece 29 downwardly into engagement with the ratchet piece 23.

By a careful consideration of Fig. 2, it 90 will be noted that the teeth of the ratchet member 21, are set to allow them a half a tooth's difference between the same and the teeth of the ratchet member 22 in the engagement of ratchet piece 23, so as to thus 95 double the number of positions at which the movable jaw 16 will be locked through the adjusting devices. It is obvious, however, when thumb piece 25 is rocked on its pivot 26, the ratchet member 21 as well as the 100 ratchet member 22 will be elevated against the tension of spring 29 out of engagement with the ratchet piece 23, so that the slide 20 will be free for movement forwardly or rearwardly to respectively increase or decrease 105 the space between the jaws 12 and 16.

Thus in operation in order to effect adjustment of the movable jaw 16, so as to snugly clamp a nut between the same and the stationary jaw 12, it is simply necessary 5 for the operator to place his thumb upon the thumb piece 25 and rock the same on its pivot 26, forcing its rear end rearwardly so as to lift the members 21 and 22 out of engagement with the ratchet piece 23. The 10 operator then shifts the slide 20 forwardly or rearwardly, as the case may be, movement to this slide being communicated to the movable jaw 16 through the toothed extensions 18 and 19 and the toothed wheel 17. When the nut has been snugly engaged 15 the operator simply releases pressure upon the thumb piece 25 and the spring 29 forces the forward end thereof downwardly and thrusts one or the other of the ratchet members 21 or 22 into engagement with the teeth of the ratchet piece. 20 It is thus obvious that my invention provides a simple inexpensive wrench which will be highly useful as a quick acting, quick adjusting nut turning implement, and which will be lasting and durable in use. 25 I claim:— 30 1. A wrench comprising a handle having a stationary jaw and a slotted extension at right angles to said jaw, a movable jaw having an extension shiftable in the slot of 35 the handle extension and provided with teeth along its said extension, a toothed wheel journaled in the angle between the handle and its said extension and engaging the toothed extension of the movable jaw, 40 an adjusting slide movable longitudinally of the handle and having a toothed portion also engaging the said toothed wheel, a ratchet piece carried by the handle, and a tilttable spring controlled ratchet member 45 carried by the said slide and engaging the said piece and having a projection extending laterally beyond one side of the handle and forming a finger piece, as described. 50 2. A quick acting and adjusting wrench comprising a longitudinally slotted handle having a ratchet jaw at one end and a rigid extension projecting therefrom adjacent and at right angles to the said rigid jaw, a movable jaw shiftable on said extension and having 55 a toothed inner portion, a toothed wheel journaled in the angle between the handle and its said extension and engaging the toothed portion of the movable jaw, a slide shiftable in the slot of the handle and having 60 a toothed portion also in engagement with the said toothed wheel, and means for adjustably securing the said slide including a movable spring controlled thumb piece mounted in connection with the slide and

projecting laterally beyond the handle, as 65 described.

3. A quick acting and adjusting wrench comprising a longitudinally slotted handle having a ratchet jaw at one end and a rigid extension projecting therefrom adjacent and at right angles to the said rigid jaw, a movable jaw shiftable on said extension and having a toothed inner portion, a toothed wheel journaled in the angle between the handle and its said extension and engaging the 70 toothed portion of the movable jaw, a slide shiftable in the slot of the handle and having a toothed portion also in engagement with the said toothed wheel, means for adjustably securing the said slide including a 75 rigid ratchet piece carried by the handle, a ratchet member engaging said ratchet piece, a thumb piece pivoted in connection with the slide and supporting the said ratchet member, and a spring carried by the slide and 80 normally holding the ratchet member in engagement with the said ratchet piece. 85

4. A quick acting and adjusting wrench comprising a longitudinally slotted handle having a rigid jaw, a movable jaw shiftable 90 in a portion of the handle toward and away from the rigid jaw, means for adjusting the movable jaw, including a slide operatively connected to the movable jaw and shiftable in the slot of the handle, a thumb piece 95 pivoted to the said slide and projecting beyond the handle, a ratchet piece carried by the handle, a ratchet member carried by the thumb piece, and engaging the said ratchet piece, and a spring carried by the slide and 100 normally holding the said ratchet member in engagement with the ratchet piece. 100

5. A quick acting and adjusting wrench comprising a longitudinally slotted handle having a rigid jaw, a movable jaw shiftable 105 in a portion of the handle toward and away from the rigid jaw, means for adjusting the movable jaw, including a slide operatively connected to the movable jaw and shiftable in the slot of the handle, a thumb piece pivoted to the said slide and having a portion projecting beyond the handle, and an extension at one side of its pivot provided with ratchet teeth and with a cut away portion, a ratchet member movable in said cut 110 away portion and also having ratchet teeth, and a rigid ratchet piece carried by the handle and with which ratchet teeth of said thumb piece and said ratchet member are engageable. 115

6. A quick acting and adjusting wrench comprising a longitudinally slotted handle having a rigid jaw, a movable jaw shiftable in a portion of the handle toward and away from the rigid jaw, means for adjusting the 120 movable jaw, including a slide operatively connected to the movable jaw and shiftable in the slot of the handle, a thumb piece piv- 125

oted to the said slide and having a portion projecting beyond the handle, an extension at one side of its pivot provided with ratchet teeth and with a cut away portion, a ratchet member movable in said cut away portion and also having ratchet teeth, a rigid ratchet piece carried by the handle and with which ratchet teeth of said thumb piece and said ratchet member are engageable, the teeth of said ratchet member being spaced apart 10 from the teeth of the thumb piece a distance equal to a tooth and a half of the ratchet piece.

THOMAS ELCANAH MILLER.
